ENVELOPE MOISTENER

Charles H. Parton, 88 Yantacaw Brook Road,
Upper Montclair, N.J.

Filed Dec. 8, 1959, Ser. No. 58,601

Term of patent 14 years

(CL. D74—10)

FIG. 1

FIG. 2

FIG. 3

FIG. 4

Fig. 1 is a top perspective view of an envelope moistener showing my new design;

Fig. 2 is a top plan view thereof;

Fig. 3 is a front elevational view, the back thereof being similar in appearance; and

Fig. 4 is an end elevational view thereof as seen from the right of Fig. 3.

I claim:

The ornamental design for an envelope moistener, substantially as shown and described.
